FILM REEL

Miguel López-Henriquez, New York, N. Y.

Application January 5, 1946, Serial No. 639,176

7 Claims. (Cl. 242—71)

1

This invention relates to a film reel and spindle mount therefor.

An object of the invention is to provide a new and useful improvement on the reel and spindle mount set forth in my copending application entitled "Film reel" Serial Number 591,693 filed May 3, 1945, which enables the film to be unwound from the center of the reel to eliminate the necessity of rewinding of the film.

A further object is to provide a construction which is much simpler, more easily assembled and adjusted than other similar types of reels.

A further object is to provide a simple and efficient means to insure that when the parts are assembled they bear definite space relations which will enable proper and easy withdrawal of the film from the reel.

A still further object is to provide a strong positive construction which will enable the reel and its supporting element to be quickly and easily with a minimum of effort, attached to the standard reel arm of a projector.

Briefly and in general terms, the reel supporting element is a simple arm to be slipped over a bushing and locked in place by a nut. The bushing receives the stub shaft of projector reel arm. The hub of the projector reel arm is surrounded by a cup-shaped collar member on the bushing and a set screw thereon engages the hub to fasten the bushing and collar in any position around the hub. The reel supporting arm at one end has rollers to pass the film, and at the other end the arm is provided with a flat flange supporting a spindle which is in general circular but has a squared portion just below its top to support the upper plate of the reel. The lower plate of the reel has a square hole to permit the passage of the squared part of the spindle. The upper end of the spindle has keys thereon and the upper plate of the reel has a circular opening with oppositely extending key-ways to receive the keys on the spindle and lock the upper plate to the spindle against turning and position it with respect to a large gap between the spokes of the upper plate through which gap the film is easily and without hindrance withdrawn from the reel.

Other features will be apparent from a consideration of the specification hereinafter when taken in connection with the accompanying drawings which form part of the specification.

The present preferred form of the invention is illustrated in the drawings, of which,

Figure 1 is a top plan view of the reel and its support,

2

Figure 2 is a side elevation of the support, showing the reel in vertical section.

Figure 3 is a fragmentary plan view of the top wheel of the reel.

Figure 4 is a fragmentary horizontal sectional view on the line 4—4 of Figure 2.

Figure 5 is a fragmentary vertical cross sectional view through the reel support showing its connection with the arm of a standard motion picture projector.

10 The reel is formed of two spaced wheels 10 and 11 respectively forming the upper and lower sides thereof. The lower wheel 11 has as usual the regularly spaced spokes 12 connecting its rim portion with its central hub portion 13 (Figure 4) and the upper plate 10 also has spokes 14 regularly spaced except at a portion where the inner end of the film 15 is withdrawn from the center of the rolled film. In this portion the spoke 15 is omitted to provide an extra large gap permitting the free exit of the film. This is in accordance with the construction set forth in the above mentioned application.

15 The central hub 11 of the upper wheel 10 has a circular hole 18 therein with oppositely extending key-ways 19—19. Fastened to the lower face of the upper wheel 10 and disposed concentric with the hole 18 therein is a dependent circular sleeve 20 provided with inner ways for ball 20 bearings 21. Fastened to the upper face of the lower wheel 11 and disposed concentric with the opening 16 therein is an upstanding smaller sleeve 22 provided with outer ways for said ball bearings. Also fastened to the upper face of the lower wheel 11 is a film supporting ring-shaped hub 23 having an upper bevelled edge portion 24 as shown for the purposes mentioned in the above mentioned application to permit the easy exit of the film from the hub when it is being unwound 25 from the reel. The hub 23 is provided with a slot 38 to facilitate the insertion of the inner end of the film thereinto preparatory to winding, and from which the end of the film may be withdrawn for withdrawal and unwinding.

20 The reel is adapted to be supported in a horizontal position as shown in Figures 1 and 2 on a supporting device which is connected to the reel arm of any 8 or 16 mm. projector. This support is provided with a vertical spindle 25, circular in 25 general cross section and provided at its top with oppositely extending keys 26—26 adapted to lie in the above mentioned key ways 19—19, and thus hold the upper wheel 10 stationary with respect to the supporting device.

25 Just below the keys 26—26 on the spindle 25

its section is squared as at 32. This squared section will pass through the squared opening 16 in the lower wheel 11 and will act as a support for the upper wheel 10 which as shown will rest thereon. It is so positioned on the spindle 25 that this disposition will hold the parts in their proper relation. The keys 26—26 aline with two opposed corners of the square portion 32.

The supporting device comprises an exteriorly threaded hollow bushing 26' adapted to receive a stub shaft 27 extending from the arm 28 of a projector, and also has adjacent the bushing at one side, a cup shaped member 29 surrounding the hub 30 of said projector arm 28 and is fastened thereto by means of a set screw 31 on the member 29 and forced into bearing contact with the periphery of the hub 30. This arrangement permits the reel arm and supporting device to be adjusted on the arm projector 28 at any desired angle by merely turning the bushing until the desired angle of support is attained when the set screw is tightened to hold it in that position.

The support for the spindle 25 is a flat flange 33 bent over from one end of an arm 34 the outer end of which supports rollers 35—35 through which the unwinding film 15 passes. The other end of this arm 34 is perforated to slip over the threaded bushing 26' and is held in place against the rear face of the cup-shaped portion of the bushing by means of a washer 36 and a nut 37, which gives certain tension to arm 34 and permits it to be adjusted at any desired angle without disturbing the adjustment of the set screw.

In the operation of the device, the two wheels 10 and 11 with the film rolled therebetween is placed on the spindle 25 by passing the spindle through the squared hole 16 whereupon it will move up until the squared portion 32 thereon abuts the under face of the upper wheel 10 at which time the end of the spindle 25 will lie in the circular hole 18 with the keys 26—26 disposed in the respective key-ways 19—19. Thus the upper wheel 10 will be held from turning while the lower wheel 11 carrying the bevelled hub 23 with the film wound around it is able to turn as the inner end of the film is pulled out in the manner described in the above mentioned application. The keys and key-ways are so arranged that when they engage, the large gap between the spokes 14 of the upper wheel 10 will lie directly in line with a line drawn through the keys 19—19 so as to definitely position the upper plate on the spindle 25 with respect to the point at which the film is withdrawn from the roll of film.

While the invention has been described in detail with respect to a present preferred form which the invention may assume, it is not to be limited to such details and form since many changes and modifications may be made in the device without departing from the spirit and scope of the invention in its broadest aspects. Hence it is desired to cover any and all forms and modifications of the invention which may come within the language or scope of any one or more of the appended claims.

Having thus described the invention, what I claim as new and desire to secure by Letters Patent is:

1. A film reel comprising upper and lower wheels, the upper wheel having a circular opening with oppositely extending key-ways therein, the lower wheel having an alined square opening therein, circular sleeves on the respective wheels and disposed in telescopic relation, ball bearings between the sleeves, a hub concentrically disposed

around the sleeves and adapted to receive a film wound thereon, the hub being disposed on the lower wheel, the upper edge of the hub being bevelled to facilitate the easy exit of the film therefrom.

2. A film reel comprising a pair of wheels, means for retaining the wheels in spaced parallel concentric relationship so that they may rotate with respect to each other, one of said wheels having a central circular opening with a keyway formed therein and the other wheel having a central non-circular opening in alignment with the circular opening in the first mentioned wheel.

3. A film reel comprising a pair of wheels, 15 means for retaining the wheels in spaced parallel concentric relationship so that they may rotate with respect to each other, one of said wheels having a central circular opening with a keyway formed therein and the other wheel having a central polygonal opening in alignment with the circular opening in the first mentioned wheel, said polygonal opening being of such a size that an inscribed circle tangential to the sides of the opening is of the same size as the opening in the 20 first mentioned wheel.

4. In a film reel support a vertically disposed spindle circular throughout most of its length and having a polygonal portion spaced a short distance from the upper end thereof with a keyed 25 portion immediately above the polygonal portion the cross sectional area of the polygonal portion being such that the circular portions of the shaft are tangential to the sides thereof.

5. A film reel comprising a first side wheel, a 30 second side wheel, means for retaining the wheels in spaced parallel concentric relationship while permitting them to rotate freely around their central axis with respect to each other, and a winding hub adapted to receive a film disposed 35 between the wheels and mounted on the first mentioned wheel so as to rotate therewith, a portion of the width of the periphery of the hub disposed adjacent the first mentioned wheel being transversely straight and parallel with the axis 40 of the wheel and the remaining portion being tapered inwardly towards the center of the reel to facilitate withdrawal of the film therefrom the tapered portion of the hub terminating intermediate the two wheels a spaced distance from 45 the second mentioned wheel.

6. A film reel comprising a first side wheel, a second side wheel, means for retaining the wheels in spaced parallel concentric relationship while permitting them to rotate freely around their 55 central axis with respect to each other, and a winding hub adapted to receive a film disposed between the wheels and mounted on the first mentioned wheel so as to rotate therewith, at least a portion of the width of the periphery of 60 the hub being tapered inwardly towards the center of the reel to facilitate withdrawal of the film therefrom the said hub terminating intermediate the two wheels a spaced distance from the second mentioned wheel.

65 7. A film reel comprising a first side wheel, a second side wheel, means for retaining the wheels in spaced parallel concentric relationship while permitting them to rotate freely around their central axis with respect to each other, and a 70 winding hub adapted to receive a film disposed between the wheels and mounted on the first mentioned wheel so as to rotate therewith the said hub being narrower in width than the distance between the two wheels and terminating 75 intermediate the two wheels a spaced distance

from the second mentioned wheel to facilitate withdrawal of the film therefrom.
